UNITED STATES PATENT OFFICE.

CHARLES M. HERRING, OF FORT WORTH, TEXAS.

ROTARY RAZOR-SHARPENING MACHINE.

1,087,536.

Specification of Letters Patent.

Patented Feb. 17, 1914.

Application filed December 16, 1912. Serial No. 737,031.

To all whom it may concern:

Be it known that I, CHARLES M. HERRING, a citizen of the United States, residing at Fort Worth, in the county of Tarrant and State of Texas, have invented new and useful Improvements in Rotary Razor-Sharpener Machines, of which the following is a specification.

This invention relates to razor stropers, and particularly to devices of this kind utilizing rotating grinding cylinders and has for an object to provide an efficient mounting for the rollers and means for operating them, and particularly, an improved blade holder adapted to function in engaging a blade with two rollers alternately, and to transmit modulations of the pressure applied. It is an important purpose to reduce the number of elements or parts involved in such a device, whereby its operation and repair will be easily understood and accomplished.

Another particular object is to give a simple construction of holder and means for securing it in engagement with a blade, making use of certain elements essential to the before mentioned functions.

A further purpose is to readily adapt a small device of this order to accommodate any form of blade, including that of the old style folding razor permitting the grinding thereof without removal of the handle.

Additional objects and advantages will appear, some being apparent from the following description and from the drawings, in which—

Figure 1 is a perspective side view of my device, Fig. 2 is a top view, thereof, Fig. 3 is a side view thereof, Fig. 4 is a detail of the operating crank, Fig. 5 is a perspective view of a blade holder in disengaged position, Fig. 6 is a similar view of a holder modified in its gripping arms, Fig. 7 is a similar view of a further modification of the same, Fig. 8 is a similar view of a still further form modified in the same particulars. Fig. 9, is an additional modification of the gripping arms, Fig. 10, is an end view of a modification of the grip structure.

There is illustrated a sharpener comprising the housing 10 formed of one piece of sheet metal, including the floor 11, and the upstanding ends 11' turned upwardly at right angles at each side of the floor and extending from front to rear of the housing. Suitable knobs 12 are attached to the under side

of the floor at proper points. Adjacent the front and rear the sides are each provided with apertures 13 in which are journaled the trunnions 14 and 15 of the rollers 16. One of these rollers has two and the other one, trunnion 14 setting nearly flush with the outer side of the ends of the housing. The other end of the last mentioned roller has an elongated trunnion provided with the teats 16' adapted to engage in the spiral slots 17 in the end of the sleeve 18 of the crank 19 by which the device is operated. It will be apparent that by this arrangement the rollers can only be turned in one direction, that is, with their adjacent surfaces moving downwardly. The rollers are provided with one gear each at adjacent ends, the gears being somewhat larger than the intermediate portions of the rolls and in mesh, whereby the two rolls are operated together, and their adjacent surfaces held in proper spaced relation, as at 20. The rolls are surfaced with any customary or suitable material for use in sharpening razors, such as leather, for instance. The ends 11' are extended upwardly some distance above the tops of the rolls, being preferably inclined downwardly toward front and rear from their middle parts, or from a point centrally over the space between the rolls, where a notch 21 or open bearing is formed in each wall for a purpose to be indicated.

Blade holders 22 are provided, which it will be observed do not have to be materially modified to adapt them to use with any of the familiar forms of blades now in use. As shown in all the figures except Fig. 10 they comprise two pivoted wings, 23 and 24, each having jaws 25 and 26 extended downwardly therefrom and adapted to engage with a blade presented therebetween. The wings and jaws are stamped integrally from sheet metal, and each adjacent each end has an ear 27 formed thereon and turned inwardly toward the opposite member, the ears being formed at the upper corners of the jaws and one member may be offset so as to receive the ears of the other member therebetween if desired. The ears are apertured and receive therethrough a long pin 28 which projects beyond the ears at each end, thereby being adapted to rest in the notches formed in the sides of the housing, allowing pivotal movement of the holders as will be described. The wings are somewhat longer than the jaws in most cases,

but this proportion is not arbitrary and may be changed as found desirable, though it is considered preferable that the wings be as nearly as possible of such length that the 5 fingers of an operator may be pressed thereupon at a point equi-distant from the pin pivot with the edge of the blade held in the device.

The wings extend about at right angles to 10 the jaws, though this is not essential, but it is desirable that the wings extend nearly in a common plane when in engaged position, so that they may be conveniently engaged by 15 respective fingers of an operator, pressed upon their upper sides, and the holder oscillated to bear the engaged blade against the rolls alternately.

The jaws may be variously shaped to engage particular kinds of blades, and in Figs. 20 5 to 9 of the drawings, there are shown various forms adapted for engagement with the particular kinds of blades shown in the respective views as presented for gripping. In Fig. 5 that form of blade consisting of a 25 rectangular blank 30 of thin sheet steel sharpened at one edge and having a piece of heavier sheet metal 31 bent over the opposite edge, is shown, and for gripping this the jaws have their outer edge portions 32 30 inset or offset from their inner portions toward the opposed jaws at a spaced distance from their pivots so as to engage the blade just within the reinforcing piece 31 on the blade. In Fig. 6 the jaws are planiform and 35 roughened on their inner sides as at 33 for engagement with the blade 34 shown in presentation, and which consists of a plain blank of sheet metal sharpened at one edge. In Fig. 7, the blade is a plain blank substantially the same as in Fig. 6, except that at 40 each corner opposite the cutting edge, short nibs 35 are projected longitudinally therefrom. For holding this blade one jaw is provided with an inwardly turned ear or 45 tooth 36, at each end. The opposite jaw is notched at the corners to receive the ears 36, and the blade is set between the jaws with the nibs engaged inwardly of the ears. In Fig. 50 8, the jaws are provided one with apertures 37 and the other with teats 38 adapted to project thereinto, and spaced for engagement of the teats through the apertures of the blades 39 and 39^a there shown. In Fig. 9 the device is adapted for use with a blade 55 40 of the old style, or with safety razor blades having a similar cross sectional form. Here, the jaws are turned abruptly outward near the ears 27, and then turned inward at an oblique angle.

60 For holding the jaws in forcible coengagement with a blade, any of the forms of holders described may have pivoted on one wing the short arm 41 adapted to project over the opposite wing a distance, and having one edge portion turned upwardly at its

outer end as at 42. On the opposite wing there is formed a curved slit 43 eccentric to the pivot of the arm 41 and spaced so as to receive the outer end of the arm freely therewithin at its outer end, when the device is initially engaged with a blade. The outer edge portion of this slit is pressed upwardly to form the locking plate 44, against which the end of the arm will strike when moved from the outer end toward the inner end thereof. The upturned side edge of the arm insures its proper engagement with the plate 44.

In Fig. 10 the holder is so modified that no fastening device will be required therefor, the two wings being formed integrally and extending in alignment for their major portions, their outer edges being turned downwardly slightly. Resilient jaw pieces 45 corresponding in form to such of those before described as may be found practicable with this form of the device are secured to the under side of the wing piece disposed close enough together to hold a blade tightly when it is presented therebetween at one end and moved slidingly into proper position for grinding, the ends of the jaws being slightly curved apart to facilitate this operation if desired.

One side of the casing or housing is provided with an opening 48 consisting of a large upper portion for the reception of the thick part of the old style razor, and a lower part, between which fingers 49 forming the sides of the opening, project inwardly into close enough proximity to engage the blade intermediately of the cutting edge and the back. By the use of this opening an old style blade may be sharpened without removal of the handle, the blade being inserted between the rolls through the opening, leaving the handle outside. The fingers 49 prevent the cutting edge from striking the lower edge of the opening 48 and becoming dulled or nicked. The fingers are so spaced as to allow some play of the blade when the back is held against the upper edge of the opening, and the opening is located at such height as to allow the blade to engage the rolls at the proper point. The fingers 49 also guard the rolls from being cut during presentation of the blade.

In use, a blade being engaged in one of the holders between the jaws, and the arm 41 forced into firm binding engagement with the locking plate, the blade will be held securely. The blade is then presented downwardly through the top of the housing, and between the rolls, until the ends of the pin 28 rest in the notches 21 in the top edges of the housing. The blade is thus held freely for oscillation into contact with either of the rolls, which is done by pressing two fingers on respective wings and alternately bearing downwardly thereon with the desired 130

amount of force while the crank is operated. It is an important advantage of this device that the degree of pressure may be most conveniently modulated to obtain the finest edge, yet permitting heavy and rapid grinding at the start, so that a minimum expenditure of time will be required for the complete sharpening of a blade.

The device has the advantage over an ordinary "stropper" in giving a "hollow ground" edge, which is generally considered to be the best edge for razors.

The machine may be constructed in an extremely small size, or may be made in larger sizes, and the holders elongated so as to hold a plurality of blades at one time, if desired. The sizes of the rolls may be varied to give the frictional area considered best for efficiency.

20 What is claimed is:

1. A sharpening machine comprising a housing, spaced grinding devices movable therein, and means to operate the grinding devices, open bearings at the sides of the 25 housing, a blade holder constructed and adapted for detachable engagement with a blade, and having a pivot element adapted to be set in the bearings, and oppositely extending wings on the holder at the upper 30 part for manual engagement to oscillate the holder.

2. A device of the class described comprising a housing, parallel grinding devices movable therein, means for operating them, 35 open bearings at opposite sides of the housing between the devices, a blade holder comprising pivoted jaws adapted for gripping engagement with a blade, lateral wings on the jaws, projections at each end of the 40 holder adapted to rest in the bearings, and means to lock the jaws upon a blade.

3. In a sharpening device having pivot bearings, and abrasive means thereadjacent, a blade holder comprising two members 45 each including a downwardly extending jaw inwardly turned ears at or near the upper corners thereof and wings extending laterally outward therefrom at their upper edges; a pin member coengaged through the 50 ears to hold the members pivotally connected, and means to lock the jaws upon an interposed blade, said wings being adapted for manipulation to oscillate the holder, the ends of the said pin being adapted to rest 55 in the bearings.

4. In a sharpening device, a blade holder comprising two pivotally connected jaws

adapted for coengagement upon a blade, each having a wing projecting laterally from the plane of the blade, an arm pivoted 60 upon the outer side of one wing, and adapted to extend transversely across the plane of adjacent jaw and engaged slidably over the opposite wing, a locking plate on the other having a curved edge eccentric to the pivot 65 of the arm in the plane of oscillation of the arm and adapted to bind the end of the arm when swung thereagainst to hold the jaws in clamping engagement with a blade.

5. In a device of the class described, a 70 holder comprising two elements each including a downwardly extending work engaging jaw, and an operating wing extended abruptly and laterally outward from the upper side of the jaw, inwardly extending apertured ears at or near the upper corners of the jaws, the ears of one adapted to overlap and register with those of the other, a pin engaged through the ears and projecting longitudinally therebeyond, an arm 80 pivoted intermediately of the wing of one element, the wing of the other having a curved slit formed therein eccentric to the pivot of the arm, the outer edge portion abutting the slit being pressed upward and 85 adapted to engage the end of the arm when swung theretoward, to hold the jaws in clamping position.

6. The combination of parallel grinding devices, an intermediate support, a blade 90 holder constructed and adapted to be pivoted on the support for oscillation into alternate engagement with the grinding devices, the holder comprising two members each of sheet metal each having one side 95 portion shaped and adapted to coöperate with the like part of the other member to grip a blade, pivotal connection between the members and means to engage said support, side portions of the members opposite said 100 grip portions being bent abruptly outward adjacent the pivotal connections to form wings adapted to receive respective fingers of an operator thereon for oscillation of an engaged blade by alternate pressure on each, 105 and means to secure the holder in engagement with the blade.

In testimony whereof I have hereunto set my hand in presence of two subscribing witnesses.

CHARLES M. HERRING.
